US0D1112225S

(12) **United States Design Patent** (10) **Patent No.:** **US D1,112,225 S**
(45) **Date of Patent:** **** Feb. 10, 2026**

(54) **SWITCH**

(71) Applicant: **Shenzhen Jiayi Electronics Co., Ltd.,**
Guangdong (CN)

(72) Inventor: **Xiaoyi Luo**, Zhejiang (CN)

(**) Term: **15 Years**

(21) Appl. No.: **29/919,253**

(22) Filed: **Dec. 2, 2023**

(51) LOC (15) Cl. **14-02**

(52) U.S. Cl.
USPC **D14/434**; D14/240
